FIG. 4.

UNITED STATES PATENT OFFICE.

EDWIN B. POTTS, OF JERSEY CITY, NEW JERSEY, ASSIGNOR TO AUTOSALES CORPORATION, A CORPORATION OF NEW YORK.

COIN-CONTROLLED VENDING-MACHINE.

1,382,384.

Specification of Letters Patent. Patented June 21, 1921.

Application filed April 11, 1918. Serial No. 227,856.

To all whom it may concern:

Be it known that I, EDWIN B. POTTS, a citizen of the United States, and a resident of Jersey City, in the county of Hudson and State of New Jersey, have invented certain new and useful Improvements in Coin-Controlled Vending-Machines, of which the following is a specification.

The object of my invention is to provide 10 a coin-controlled vending machine embodying certain improvements and advantages over machines of this class heretofore constructed.

The main feature of my invention resides 15 in the fact that the entire movement of the delivery mechanism is controlled by the hand-operable part which the purchaser operates from the outside of the casing. That is to say, the purchaser controls not only 20 the forward movement of the delivery mechanism and the parts connected therewith, but also the return movement of the mechanism and the connected parts. This enables me to dispense altogether with return 25 springs, with the result that the machine is easy and noiseless of operation. Also, the absence of all springs results in a structure of extreme simplicity, with no liability of the parts getting out of order.

I accomplish the foregoing results by 30 means of a construction which causes the actuating member for the delivery mechanism to be actuated partly through the medium of the deposited coin and partly by means 35 independent of the coin.

The underlying principle of my invention 40 may be mechanically carried out in many ways, but in the accompanying drawings I have shown a machine embodying my invention in a form which I have found to be practical. I will have it clearly understood, however, that the machine shown in these 45 drawings is merely an illustrative embodiment of my invention and is not to be considered as a limitation.

In these drawings—

Figure 1 shows a rear elevation of a machine provided with my invention, the operative parts being shown in position about to 50 be actuated by the deposited coin, and the back of the machine being omitted so as to show the parts within;

Fig. 2 is a longitudinal section on line 2—2 of Fig. 1, looking in the direction of

the arrows, this figure including the back 55 of the casing which is omitted from Fig. 1;

Fig. 3 is a transverse cross-section on line 3—3 of Fig. 1, looking downwardly;

Fig. 4 is a view similar to Fig. 1, showing the parts at approximately the end of 60 their movement under the action of the coin; and

Fig. 5 is a longitudinal cross-section approximately on line 5—5 of Fig. 4, looking 65 in the direction of the arrows.

To illustrate the different features and parts of my invention, I have shown the same applied to a machine particularly adapted for use in theaters. These machines, as is well known, are made as small as possible, particularly as to depth, and my invention is especially adapted to be employed in small machines of this kind, owing to the simplicity and compactness of construction 70 which the use of my invention produces. 75

In the accompanying drawings, the outer casing of the machine is as a whole indicated by C. This casing may be of any suitable construction and is shown in the drawings as consisting of two sections—a front section 1 and a rear section 2 which is adapted to be secured to a suitable support, such as a theater chair or the like. The front section 1 is separable from the rear section 2, and the two sections are intended to be 80 locked together in closed position. 85

Inside of the casing C is mounted a magazine, indicated as a whole by M, of any suitable construction. The magazine may be secured to the front section in any suitable manner. 90

Below the magazine M is mounted a delivery member which I have shown in the drawings in the form of a semicylinder 3. This delivery cylinder is at its ends provided with disks 4 and 5 which are provided with pins or studs 6 by means of which the cylinder is rotatably mounted in the side walls of the casing. Adjacent the disk 5 is fixed a pinion 7 which is rigid with 100 the disk 5. Pins 8 or any other suitable means may be employed for rigidly connecting the disk 5 and pinion 7 together, so that rotation of the pinion will cause rotation of the delivery cylinder 3. The teeth 95 of the pinion 7 are constantly in mesh with the teeth of the rack bar 9 which is carried by or forms the lower end of the vertically 105

reciprocating plate or bar 10. This bar is conveniently mounted on the side wall of the casing by means of headed studs 11 which engage in elongated slots 12 formed in the bar 10. The vertical bar 10 is provided with a transverse extension 13 having a slot 14.

The bar 10 is actuated up and down by the bell-crank lever indicated as a whole by D.

- 10 This lever is pivotally mounted on the stud 15 projecting inwardly from the front wall 1 of the casing, and comprises the arms 16 and 17. The arm 16 is at its free end provided with a pin 17 arranged to engage in 15 the slot 14 of the reciprocating bar 10. The arm 17 of the bell-crank lever D is at its free end provided with a pin or stud 18 which projects forwardly through the opening 19 in the front wall of the casing into the coin- 20 chute or passage 20 of the supplemental casing C' attached to the front wall of the main casing. The supplemental casing C', which may be of any approved construction, has mounted thereon the coin-carrier 21 which is 25 shown in the form of a disk provided with a coin-receiving recess or opening 22. The coin-carrier 21, which operates in the coin passage or chamber 20, is pivotally mounted on the stud 23 which is at its outer end connected with a suitable hand-operable member, such as a knob 24.

The upper end of the arm 17 of the bell-crank lever D is provided with an extension 25 which is normally out of the path of movement of the pin 26 projecting rearwardly from the coin-carrier into the plane of said extension, as best shown in Fig. 5. The function of the parts 25 and 26 will be presently explained.

- 40 The operation of the mechanism as above described may briefly be stated as follows: When a proper coin is inserted into the coin-entrance slot 27 at the top of the supplemental casing C', it passes down the coin chamber 20 to the coin-carrier 21. This coin-carrier is freely rotatable at all times, and if the deposited coin does not at once fall into the coin-seat 22, it will do so when the coin-carrier is rotated sufficiently to 45 bring this seat into alignment with the coin. When the coin-carrier is thereupon rotated in the direction indicated by the arrow *a* in Fig. 1, the deposited coin N will be carried down the coin passage 20 until the 50 lower edge of the coin strikes the forwardly projecting pin 18 of the bell-crank lever D. The normal position of the bell-crank lever D and the connected delivery mechanism is shown in Fig. 1, where the deposited coin N 55 is shown as having just reached the pin 18. It will be clear from Fig. 1, that further rotation of the coin-carrier 21 by means of the hand-knob 24 in the direction of the arrow *a* will rock the bell-crank lever D in 60 the direction indicated by the arrow *b*.

This rocking of the bell-crank lever D, in the particular construction illustrated, will extend from the position shown in Fig. 1 to the position shown in Fig. 4, where the bell-crank lever D and the connected delivery 70 mechanism are shown as having reached their extreme limit of movement under the action of the deposited coin. It will be clear from Fig. 4 that further rotation of the coin-carrier in the direction of the arrow *a* 75 will cause the coin N to be discharged from between the pin 18 and the coin-seat of the coin-carrier, the discharged coin falling through the opening 28 on to the bottom plate 29 of the coin-chamber 30 formed between the front plate of the magazine and the front wall of the casing. It will be clear from the foregoing that when the parts have reached the position illustrated in Fig. 4, the coin has performed its usefulness as 80 an actuating member or connection and is, therefore, ready to drop out of action.

It should be made clear that the movement of the bell-crank lever D by means of the deposited coin from its normal position, 90 as shown in Fig. 1, to the position shown in Fig. 4, does not cause the delivery of any article. By means of the slot-and-pin connection between the lever D and the bar 10, the rocking of the lever D from the position shown in Fig. 1 to the position shown in Fig. 4 moves the bar 10 upwardly, and this upward movement of the bar 10 rotates the delivery cylinder 3 from the position shown in Figs. 1 and 2 to the position shown in 100 Figs. 4 and 5. It will be seen from Fig. 2 that in the normal position of the delivery cylinder 3, the bottom package P rests on the upper surface of the cylinder. When the cylinder has been rotated a half revolution 105 during the movement of the lever D under the action of the deposited coin, the bottom package P lies within the cylinder, as shown in Fig. 5. It is, therefore, necessary to give the delivery cylinder another half revolution 110 before delivery of the bottom package P can take place. This further movement of the delivery cylinder 3 is brought about by the coin-carrier 21 without the intervention of the deposited coin and in the absence thereof, as may be seen from Figs. 4 and 5. Referring to these figures, it will be clear 115 that further rotation of the coin-carrier 21 in the direction of the arrow *a* will cause the pin or projection 26 of the coin-carrier to 120 bear against the extension 25 of the lever D and thereby rock said lever back to normal position, as indicated by the arrow *b'* in Fig. 4. During this return movement of the lever D the reciprocating bar 10 is pushed 125 downwardly and the delivery cylinder is rotated in the direction of the arrow *c* from the position shown in Fig. 5 to the position shown in Fig. 2. During this final movement of the delivery cylinder, the bottom 130

package P drops out of the cylinder on to the plate 31 at the bottom of the casing, whence it may be moved by the purchaser through one of the side openings 32.

- 5 The pin 26 of the coin-carrier 21 actuates the lever D and all the parts connected therewith back to normal position. When the lever D is in normal position, the extension 25 is out of the path of movement of 10 the pin 26 of the coin-carrier, so that the latter is free to be rotated in either direction in the absence of a coin without causing movement of the lever D.

It will be clear from Fig. 4 that upon the 15 discharge of the coin from between the coin-carrier and the pin 18 of the lever D, it is immaterial in which direction the coin-carrier 21 is then rotated to complete the delivery operation of the lever D, for the 20 pin 26 of the coin-carrier will engage the extension 25 in either direction of rotation of the coin-carrier.

It will be seen from the above that the 25 entire movement of the actuated parts—both the forward and the return movement—is under the control of the hand-operable coin-carrier 21. This produces not only a noiseless operation of the machine, due to the absence of springs, but also produces a 30 slow, easy and safe delivery of the goods. In small machines where there is essentially but a limited space for the delivery of the goods, the delivered package is liable to get caught between the delivery member and 35 the wall of the casing by the sudden return of the delivery member under the action of a return spring. Another objection to return springs is that they unnecessarily complicate the machine and are liable to get out 40 of order, thereby rendering the operation of the machine uncertain.

The noiselessness of the operation of a 45 machine constructed after my invention, is of special advantage in machines intended to be operated in theaters where people demand uninterrupted silence and quiet in order to enjoy the performance. A machine which is noisy in operation would, therefore, be objectionable in a theater.

50 Although I have herein shown and described a specific form of a machine embodying the various features of my invention, I would have it understood that in the broad aspect of my invention, these features 55 may be embodied in various forms without departing from the scope of my invention as defined in the appended claims. It will also be clear, that in the broad aspect of my invention, the precise function 60 of the actuating member D is immaterial, and where, as in a vending machine, the member D is employed to actuate delivery mechanism, the particular form or construction of that mechanism is immaterial. In 65 the drawings I have shown a delivery mech-

anism in the form of a semi-cylinder, merely by way of illustrating a suitable form of mechanism. The delivery mechanism shown in the drawings and its operative connections with the lever D do not in 70 and of themselves form part of my present invention, as they are set forth in the co-pending application of Anthony Coseglia, Serial No. 186,843, filed August 18, 1917.

Having thus described my invention, what 75 I claim as new and desire to secure by Letters Patent of the United States, is

1. In a coin-controlled vending machine, delivery mechanism, a movable member adapted to cause operation of said mechanism when said member is moved from normal to full-operated position, a hand-operable coin-carrier for conveying the deposited coin into position to actuate said member part-way from normal to full-operated 80 position, and means independent of said coin for actuating said member the rest of the way to full-operated position through the medium of said coin-carrier.

2. In a coin-controlled machine, a hand-operable actuating member, a second member adapted to be actuated by said first member, said members being normally disconnected from each other, means whereby said members become operatively connected 90 through the deposited coin for preliminary actuation of said second member, and means independent of the deposited coin for operatively connecting said members for further actuation of said second member by 95 100 said first member.

3. In a coin-controlled vending machine, delivery mechanism, a movable member adapted to cause operation of said mechanism when said member is moved from normal to full-operated position, a hand-operable coin-carrier for conveying the deposited coin into position to actuate said member part-way from normal to full-operated 105 position, and coöperating means on said member and said coin-carrier for actuating said member the rest of the way to full-operated position when said coin-carrier is operated, said coöperating means being 110 wholly independent of the deposited coin. 115

4. In a coin-controlled vending machine, delivery mechanism, a movable member adapted to cause operation of said mechanism when said member is moved from normal to full-operated position, a rotatable 120 coin-carrier for conveying the deposited coin into position to actuate said member part-way from normal to full-operated position, whereupon the coin is discharged from said coin-carrier, and means independent of 125 said coin for actuating said member the rest of the way to full-operated position when said coin-carrier is rotated either way after the discharge of the coin.

5. In a coin-controlled vending machine, 130

delivery mechanism, a movable member adapted to cause operation of said mechanism when said member is moved from normal to full-operated position, a hand-operable coin-carrier for conveying the deposited coin into position to actuate said member part-way from normal to full-operated position, whereupon the coin is discharged from said coin-carrier, and means operable only after the discharge of said coin and independent thereof for actuating said member the rest of the way to full-operated position through the medium of said coin-carrier.

6. In a coin-controlled machine, a pair of pivoted members normally disconnected, means for operatively connecting said members for a limited amount of movement through the medium of a coin on one of said members, and means independent of said coin for operatively connecting said members for further movement after the coin has ceased to act on said members.

7. In a coin-controlled machine, a movable device having a part arranged to be engaged by the deposited coin, a coin-carrier for carrying the deposited coin into engagement with said part for operating said device a predetermined amount, said device having a second part, and a member connected with said coin-carrier for engaging the second part of said device and thereby operating said device a further amount independently of the coin.

8. In a coin-controlled machine, a movable device having a part arranged to be engaged by the deposited coin, a rotatable coin-carrier for carrying the deposited coin into engagement with said part for operating said device a predetermined amount, said device having a second part, and a pin or projection on said coin-carrier for engaging the second part of said device when said coin-carrier is rotated in either direction after the action of the coin on said first mentioned part, whereby said device is actuated by said coin-carrier to full-operated position independently of the coin.

9. In a coin-controlled machine, a piv-

oted lever provided with a pin arranged to be engaged by the deposited coin, a rotatable coin-carrier for carrying the deposited coin into engagement with said pin for operating said device a predetermined amount, an extension provided on said lever, and a projection on said coin-carrier adapted to engage said extension when the coin-carrier is rotated after action of the coin on said pin, whereby said lever is actuated by said coin-carrier to full operated position independently of the coin.

10. In a coin-controlled vending machine, a rotatable delivery member requiring a complete revolution for every delivery operation, a hand-operable coin-carrier, and operative connections between said coin-carrier and said member for actuating said member for approximately the first half of its revolution by means of the coin on said carrier, said connection including means for actuating said member during the other half of its revolution by means of said coin-carrier independently of the coin.

11. In a coin-controlled machine, a movable member mounted to operate in opposite directions, a rotatable coin disk for actuating said member in one direction by means of the deposited coin when the disk is rotated forwardly, and means on said coin disk for actuating said member in the opposite direction independently of the coin during the continued forward rotation of the disk.

12. In a coin-controlled vending machine, a delivery member mounted to have a predetermined amount of movement from normal position and back to normal position during every operation of the machine, a rotatable coin disk controlled from the outside of the machine, and means whereby the complete movement of said member out of and back into normal position is controlled by said coin disk partly through and partly without the deposited coin during the forward rotation of the disk.

In witness whereof I hereunto subscribe my name this 8th day of April, 1918.

EDWIN B. POTTS.
